UNITED STATES PATENT OFFICE

2,364,960

SINK STRAINER

Maude Dunn, Birmingham, Ala.

Application March 23, 1944, Serial No. 527,812

7 Claims. (Cl. 4—291)

This invention relates to the class of strainers and pertains particularly to improvements in strainers such as are used in the drain openings of sinks and the like.

A primary object of the present invention is to provide a sink drain strainer in which there is provided a flexible mesh bag of suitable metal adapted to be supported in a frame structure within the drain opening, such bag being designed so that it may be partially turned inside out to effect the easy and quick removal of debris therefrom.

Another object of the invention is to provide a sink strainer unit of the character stated in which the metal fabric bag is slidably coupled at its bottom with an adjustable securing element whereby the bag may be stretched out and held in such condition while the strainer is in use, the bottom securing means for the bag being readily releasable to permit the turning of the bag for the emptying of the contents thereof.

Another object of the invention is to provide an improved sink strainer of the character stated wherein the metal mesh bag is detachably secured to a carrying frame, thereby permitting the ready removal and replacement of the bag when necessary.

Other objects and advantages of the invention will become apparent as the description of the same proceeds and the invention will be best understood from a consideration of the following detailed description taken in connection with the accompanying drawing forming a part of this specification, is being understood, however, that the invention is not confined to a strict conformity with the showing of the drawing but may be changed or modified so long as such changes or modifications are within the scope of the appended claims.

In the drawing:

Figure 1, is a view in top plan of the strainer unit embodying the present invention.

Figure 2, is a vertical section taken substantially on the line 2—2 of Figure 1.

Figure 3, is a partial section taken upon the line 3—3 of Figure 1.

Figure 4, is a partial section through the bottom part of the strainer taken on the dotted line 4—4 of Figure 1.

Figure 5, is a horizontal section taken upon the line 5—5 of Figure 2.

Referring now more particularly to the drawing it will be seen that the device of the present invention comprises a frame unit generally designated F which is designed to be introduced into

the usual sump which forms the drain for a kitchen sink.

The frame F comprises a bottom plate 10 and a top ring or collar 11 connected together by a number of posts 12, here shown as being four in number. However, any number of such posts may be used and therefore the invention is not to be understood as being limited to this prescribed or shown number.

10 The collar 11 is defined by an encircling laterally extending flange 13 which, when the device is in working position, is flush with the bottom of the sink in which it is mounted.

Between the collar and the flange, the flange 15 is provided with a plurality of apertures 14 for the purpose hereinafter stated.

15 The bottom plate 10 has a number of drain apertures 15 therein and at the center of this plate there is fixed a guide post 16 on which is 20 slidably mounted the collar 17. The lower end of this collar is integral with the annular flange 18 which is provided with a plurality of apertures 19 for the purpose hereinafter described.

25 Adjacent the bottom end of the post 16 there is fitted in a suitable slot, not shown, in the post, the latch 20. This latch is of the type commonly found upon an umbrella shaft for maintaining the runner in place when the umbrella is opened or closed and it is spaced above the bottom 30 plate 10 of the present device a distance only slightly greater than the length of the sleeve 17.

At its upper end the post 16 has the relatively large flat head 21 which prevents the slide 17 from escaping from the post.

35 Within the frame there is suspended a mesh strainer bag which is generally designated 22. This bag is formed of a suitable metal fabric and is preferably in a number of sections, designated 23, the longitudinal or side edges of which are 40 suitably coupled or secured together by the links or clasps 24.

The bag is suitably tapered to fit the taper of the frame which, as shown, is of materially greater diameter at its top end than at its bottom, and the lower end edges of the sections 24 have attached thereto a means for coupling the sections with the runner flange 18. Such means is here shown as comprising sector plates 25, each of which carries a hook 26 which is engaged in an opening 19 of the runner flange, as is shown in Figure 4.

45 The top edges of the sections 23 of the fabric bag are also provided with suitable means for attaching them to the collar 11. Such means is 50 here illustrated as comprising the arcuate metal

strips 27, each of which carries a suitable number of hooks 28 for connection in the apertures 14 between the collar and the flange 13. Thus it will be seen that the bottom part of the bag is coupled with the runner or slide 17 while the top edges of the bag section are attached to the collar 11 and the sections 23 of the bag are of such length that when the runner 17 is secured beneath the latch 20 the bag will be drawn out fairly tightly within the frame.

While the lower ends of the bag section have here been illustrated as attached to plate segments 25 and the top edges are shown as attached to arcuate strips 27, it is to be understood that the invention is not limited to this specific method of securing the bag to the frame. Also it is to be understood as being within the purview of the present invention to form the strainer bag as a single unit as well as in sections. The formation of the bag in sections has the advantage that if one portion of the mesh becomes broken that particular section can be removed and replaced without having to discard the entire bag. However, it will be readily apparent that the bag may be made as a single piece of material if desired.

As previously stated, the present device, when in use, will be disposed in the sink drain opening so that as waste liquids are discharged into the sink they will flow over the flange 13 into and through the mesh strainer bag and solid matter carried by the liquid will be trapped in the bag. When it is desired to empty the strainer the latch 20 is depressed so as to release the slide collar 17 and the collar is run up on the post 16 so as to partially turn the bag inside out. The entire frame may be removed from the sink drain opening when the strainer bag is so turned so that the material therein can be thrown into a garbage receptacle or otherwise disposed of.

I claim:

1. A sink strainer of the character stated, comprising a frame having spaced top and bottom members, a mesh bag within the frame and secured at its top to the frame top member, and means for securing the bag in stretched out position in the frame and to the bottom member of the frame.

2. A sink strainer of the character stated, com-

prising an open frame having an annular top and a bottom member, a metallic mesh bag disposed within the frame, means detachably securing the top of the bag within the annular member, and means for detachably securing the bottom central part of the bag to the bottom member.

3. A sink strainer of the character stated, comprising an open frame having an annular top portion and a bottom portion, and a mesh bag suspended within the frame and attached at its top edge to said annular top portion, said bag being vertically divided into a number of sections secured together along their adjacent edges.

4. A sink strainer of the character stated, comprising a frame consisting of a top annular member, a bottom member and a plurality of posts connecting said members, a metal fabric bag suspended within the frame and attached at its top edge to said annular member, a post secured to said bottom member, a sliding connection between the bottom of the bag and said post, and means for securing the bag to the post against movement relative thereto.

5. A strainer construction as set forth in claim 4, in which the connection between the bag and the post comprises a sleeve slidable on the post and said securing means comprises a latch carried by the post adjacent the bottom member, beneath which latch the slide is detachably engaged.

6. A sink strainer comprising a frame consisting of a top annular member, a bottom perforated plate and post connecting the plate with the annular member, a metallic mesh bag within the frame and attached at its top edge to the annular member, the bag having a central bottom opening, a post secured to the center of said plate and standing vertically in the frame and passing through said central opening of the bag, a sleeve attached to the bag concentric with said opening and encircling the post, and means carried by the post adjacent the plate for securing said sleeve against movement on the post.

7. A sink strainer as set forth in claim 6, in which said bag is formed in a plurality of separable portions and each of said portions is detachably connected with the annular member and with the sleeve.

MAUDE DUNN.
